lever 75 to turn counter-clockwise and bring the roller 79 into rolling contact with the lifting arm 73, thereby causing the arm 73 to move upward.

The movement of the arm 73 is governed by the cycle of operation of the two motors 43 and 44. The piston rod of motor 43 is directly connected to the push rod 42 and the piston rod of the motor 44 connected to the back of the motor 43 which is slidably mounted in suitable guides. On extending the piston rods of both motors the arm 73, through movement of the carriage 33, is raised to its topmost or kick-out position. When the piston rod of the motor 43 is withdrawn, the arm 73 is permitted to drop to its pipe receiving position. By withdrawing the piston rod of the motor 44, the motor 43 is displaced in its guides so as to impose further movement upon the push rod 42 and the carriage 33 whereby the arm 73 is lowered to its bottom position and the pipe carried thereby deposited upon the cradle.

Although not specifically shown, the double-acting motors 43 and 44 are connected to a suitable fluid pressure source and there are provided individual manually operated valves for admitting fluid to each of the motors.

As shown in Figure 6, removable pipe-supporting cradles 82 are inserted in the center of the stand and, since they are of various sizes, can be exchanged readily to accommodate pipes of different diameters to insure that the axes of the pipes will be coincident with the axis of the testing apparatus. Two bolts 83 extend outward from the cradle and serve as lifting lugs for aiding in the removal and the positioning of the cradles 82 within the frame. The pipe clamping device, which is actuated by movement of the carriage 53 as specifically shown in Figure 5, includes a curved arm 84 pivotally secured by a pin 85 within the frame 67. The arm is provided at its pivotal point with a counterweight 86 and at its lower end with a roller 87. The counterweight 86 insures that the arm will be in its non-clamping position, as shown in Figure 5, when the carriage 53 has been moved to the right. After a pipe has been lowered into and inserted in the pipe testing position within the cradle, the push rod 65 is actuated to move the carriage 53 to the left thereby causing the spring plate 63 to urge the roller 87 to the left, thus to rotate the clamping arm 84 clockwise and into its clamping position. When the clamping arm makes contact with the pipe to be clamped, the spring 62 is compressed by continued movement of the carriage thereby providing a cushioned clamping force against the pipe. To release the clamping arm 84 from its pipe engaging position the carriage 53 is moved to the right thereby permitting the arm 84 to rotate counter-clockwise into its non-clamping position.

For detachably securing the frame 67 between the two tension bars 11, there is shown in Figure 6 a quickly releasable curved locking arm 88, threaded at its outer end, which is pivotally secured to the frame 67 by means of a pin 89. A slidably notched sleeve 91 is retained on the arm 88 by a nut 92 and when the outer end of the arm is passed through one of the openings in the tension bars, the nut 92 is drawn up so that the sleeve 91 is firmly pressed into locking engagement with the tension bar 11, thereby preventing the frame 67 from moving out of position with respect to the stand 19.

Depending upon the length of the pipes to be tested, as many of the units as will be necessary to provide an adequate support for the pipes may be spaced along and quickly secured to the tension bars of the apparatus. Inasmuch as the cradle inserts may be removed from their frames, replacement by those which will accommodate pipes of a different diameter can readily be accomplished without undue delay or interference with the testing procedure. Then, too, though the cradles and clamping units have been shown as applied to a unit for testing pipes individually, they are adapted to be applied to a unit in which two or more pipes may be tested simultaneously.

In accordance with the provisions of the patent statutes, I have explained the principle and operation of my invention and have illustrated and described what I consider to represent the best embodiment thereof. However, I desire to have it understood that within the scope of the appended claims, the invention may be practiced otherwise than as specifically illustrated and described.

I claim:

1. For use in combination with pipe testing apparatus and the like, a cradle, a pipe receiving, lowering and

ejecting member pivotally supported at one end above said cradle and having an element projecting outward from the front side and at substantially right angles therefrom to form a support for a pipe engaged thereby, a lever pivotally supported between its ends below said cradle, one end of said lever slidably engaged with the rear side of said member, an element movable transversely of said cradle and in engagement with the opposite end of said lever adapted to turn said lever about its pivot thereby to raise and lower said member from the pipe ejecting to the pipe testing position, means in engagement with and to shift said element thereby to lower said member from its pipe ejecting to its pipe receiving position, and separate means in engagement with said last-mentioned means for shifting said element an additional amount thereby to lower said member and the pipe carried thereby to deposit the pipe in its testing position on said cradle.

2. For use in combination with pipe testing apparatus and the like, a cradle, a pipe receiving, lowering and ejecting member pivotally supported at one end above said cradle and having an element projecting outward from the front side and at substantially right angles therefrom to form a support for a pipe engaged thereby, a lever pivotally supported between its ends below said cradle, one end of said lever slidably engaged with the rear side of said member, an element movable transversely of said cradle and in engagement with the opposite end of said lever adapted to turn said lever about its pivot thereby to raise and lower said member from the pipe ejecting to the pipe testing position, means in engagement with and to shift said element thereby to lower said member from its pipe ejecting to its pipe receiving position, and separate means in engagement with said last-mentioned means for shifting said element an additional amount thereby to lower said member and the pipe carried thereby to deposit the pipe in its testing position on said cradle, and clamping means for securing a pipe upon said cradle and means for actuating said clamping means.

3. For use in combination with pipe testing apparatus and the like, a removable cradle, a pipe receiving, lowering and ejecting member pivotally supported at one end above said cradle and having an element projecting outward from the front side and at substantially right angles therefrom to form a support for a pipe engaged thereby, a lever pivotally supported between its ends below said cradle, one end of said lever slidably engaged with the rear side of said member, an element movable transversely of said cradle and in engagement with the opposite end of said lever adapted to turn said lever about its pivot thereby to raise and lower said member from the pipe ejecting to the pipe testing position, means in engagement with and to shift said element thereby to lower said member from its pipe ejecting to its pipe receiving position, and separate means in engagement with said last-mentioned means for shifting said element an additional amount thereby to lower said member and the pipe carried thereby to deposit the pipe in its testing position on said cradle, and clamping means for securing a pipe in the testing position upon said cradle comprising a lever pivotal between its ends, one end of said lever so formed as to engage an arcuate portion of a pipe to be clamped, an element movable transversely of said cradle and in engagement with the opposite end of said lever, and means in engagement with and adapted to shift said element thereby to pivot said lever into its pipe clamping position.

4. For use in combination with pipe testing apparatus and the like, a plurality of removable cradles, a pipe receiving, lowering and ejecting member pivotally supported at one end above and adjacent each one of said cradles and having an element projecting outward from the front side and at substantially right angles therefrom to form a support for a pipe engaged thereby, a lever pivotally supported between its ends below each of said cradles, one end of said lever slidably engaged with the rear side of said member, an element adjacent to and movable transversely of each of said cradles and in engagement with the opposite end of said adjacent lever adapted to turn said lever about its pivot thereby to raise and lower said adjacent member from the pipe ejecting to the pipe testing position, means in engagement with and adapted to shift all of said elements simultaneously thereby to lower said members from their pipe ejecting to their

pipe receiving positions, separate means in engagement with said last-mentioned means for shifting simultaneously all of said elements an additional amount thereby to lower all of said members and the pipe carried thereby to deposit the pipe in its testing position on said cradles and clamping means adjacent each cradle for securing a pipe in the testing position comprising a lever pivotal between its ends, one end of each of said levers so formed as to engage an arcuate portion of a pipe to be clamped, an element movable transversely of said cradle in engagement with the opposite end of said lever, and means

in engagement with and adapted to shift simultaneously all of said elements thereby to pivot said levers into their pipe clamping positions.
